UNITED STATES PATENT OFFICE

2,465,742

CASTER

Charles R. Nalle, Philadelphia, Pa.

Application February 1, 1945, Serial No. 575,625

11 Claims. (Cl. 16—42)

1

This invention relates to adjustable casters or glides for articles of furniture etc., by which leveling or steadyng of the supported article may be effected to compensate for warping or other irregularities of the article itself and/or the floor or platform on which the article is standing.

The principal object of the present invention is to provide a simple and efficient form of device, which can be readily applied to the legs of chairs or tables, etc., or to the bases of cabinets etc. without necessitating any harmful hammering or pounding on the glide or caster per se to effect installation thereof.

The device of the present invention comprises a simple form of internally threaded socket including a circumferentially pronged base and a central perpendicularly elongated neck; wherein the neck may be initially inserted in a preboring formed in the article of furniture; and wherein the socket, without the glide or caster attached thereto, may be installed and secured in place by a sharp blow directed against the base of the socket, to drive the prongs thereof into the wood or other material of which the article is formed.

In the elongated neck is loosely confined a radially expandable and contractible retainer in the form of a sleeve, cap, or nipple which is adapted to attach itself automatically to the stem of the floor-engaging part of the caster structure, when the stem is threaded deeply into the socket, after the latter has been installed.

The retainer is adapted to snap over a head formed on the stem of the floor-engaging element to move freely in the neck of the socket with the stem and maintain the stem in the socket against subsequent accidental removal therefrom during future handling of the article or sliding thereof over the floor, from place to place.

The construction and operation of the device will be more fully disclosed hereinafter, reference being had to the accompanying drawings of which:

Fig. 1 is a vertical sectional view which shows the preferred form of the device with the socket installed in an article of furniture and the stem of the glide initially entering the loose retainer within the neck of the socket to hold the stem in the socket thereafter;

Fig. 2 shows the head of the stem fully inserted in the retainer;

Fig. 3 shows the threaded stem of the glide backed out of the internal threads in the base of the socket, with the retainer preventing complete withdrawal of the stem from the socket;

Fig. 4 is a detail view of the retainer;

Fig. 5 is a sectional plan view taken on the line 5—5, Fig. 1;

Figs. 6, 7 and 8 are views corresponding to Figs. 2, 3 and 4, respectively, but showing a modified form of stem and retainer;

2

Figs. 9, 10, 11 and 12 are views similar to Figs. 1, 2, 3 and 4 respectively but showing a still further modified form of the invention;

Figs. 13, 14 and 15 correspond to Figs. 1, 3 and 4 respectively and illustrate another modified form of the invention; and

Fig. 16 illustrates a modification of that form of the invention shown in Fig. 14.

As shown in Figs. 1, 2 and 3, the socket section 10 A of the caster structure of the present invention includes a hollow polygonal cup-like base 1, including a bottom plate 2 and integral perpendicular side walls 3, 3 which, at the intersections of the adjacent angularly disposed parts of the perimeter of the base 1 are sharply pointed and project perpendicularly to the plane of the bottom 2 to form prongs 4, 4 for securing the device to the lower end of the leg of a chair or table etc. or to the underside of the bottom of a cabinet etc.

20 Within the polygonal base 1 is housed a similarly shaped internally threaded nut 5, for receiving external threads 6 on the stem 7 of the caster or glide section B of the caster structure C.

The socket section A also includes a hollow 25 axially elongated thimble or sleeve 8 which preferably is provided with a closed end 9. The thimble or sleeve 8 is adapted to enter a preboring 10 formed in the article of furniture etc. D with which the caster structure C is to function.

The opposite open end of the thimble or sleeve 8 is provided with a circumferential, circular or polygonal flange 11 (see Fig. 5) which is disposed in a plane parallel to the base plate 2 and lies on the upper surface of the nut 5, within the cup-like base 1.

30 The upper edges of the side walls 3, 3 of the base 1, intermediate the prongs 4, 4 are provided with tongues 12, 12 which are bent radially inward over the top of the peripheral flange 11 of the thimble 8, to secure the thimble 8, the nut 5, and the base 1, together as a unit, to form the socket section A of the caster structure C.

35 Loosely mounted in the thimble 8, between the closed end 9 thereof and an internal annular shoulder 13 formed by the inner upper surface of the nut 5, the socket section A is provided with a radially expandable, inherently contractible retainer E, for securing the stem 7 of the caster or glide section B in the socket section A of the caster 40 structure C.

In that form of the invention shown in Figs. 1 to 4 inclusive, the retainer E is in the form of a cylindrically coiled spring consisting of a plurality of axially abutting spiral convolutions 15, 15, of 45 substantially equal diameters. One or both ends of the retainer E is formed of terminal convolutions 15a, 15a of slightly smaller diameter than the coils 15.

50 The insertable end of the stem 7, i.e. the end 60 opposite to that occupied by or attached to the

floor-contacting element of the caster or glide section B, is provided with a neck 16, of reduced diameter relative to the outside diameter of the threads 6 of the stem 7, and a frusto-conical head 17 having a base of substantially the same or slightly larger diameter than the neck 16, with a circumferential groove 18 formed in said neck contiguous to said base and into which one of the terminal coils 15a of the retainer E is adapted to be seated, to lock the retainer to the stem so that the latter cannot be totally removed from the socket A after the stem of the caster unit B has once been installed in the socket.

The retainer E is loosely confined in the thimble 8 and its axial length is sufficiently greater than the internal diameter of the thimble 8 to keep the retainer from turning crosswise to the axis of the thimble, whereby the axis of the retainer is at all times maintained roughly in alignment with the axis of the thimble.

With the caster unit B entirely separated from and remotely actuated with respect to the socket A, said socket is first installed in the article D by inserting the closed end of the thimble or sleeve 8 in the boring 10, which has been previously provided in the article.

The sleeve or thimble 8 is inserted into the boring 10 until the tips of the prongs 4 engage the surface of the article surrounding the boring 10, whereupon a sharp blow directed against the base plate 2, in the direction of the axis of the sleeve 8, will drive the prongs 4 into the article D, until the inturned tongues 12 solidly engage the underside of the article D.

The frusto-conical head 17 of the stem 7 of the floor-engaging section or element B is then slipped axially through the internal threads 14 of the nut 5, after which the threads 6 of the stem 7 are placed in threaded engagement with the threads 14 of the nut 5. The stem 7 is then rotated and thereby threaded into the nut 5, until the small end of the head 17 of said stem engages the small terminal convolution 15a at one end of the retainer E.

Continued screwing of the stem 7 into the nut 5 moves the retainer E into the position shown in Fig. 1. Still further turning of the stem 7 in the nut 5 drives the frusto-conical head 17 of the stem through the small convolution 15a, causing it to expand radially, while the retainer E is held against the closed end 9 of the thimble 8. The axial movement of the stem 7, by the turning of the stem in the nut 5, moves the head 17 up into the retainer E until the small terminal convolution 15a of the retainer spring E snaps over the shoulder formed by the base of the frusto-conical head 17 and enters the annular groove 18 formed in the stem under the head 17 thereof.

The retainer E is now permanently secured to the stem 7 and, as shown in Fig. 3, backing of the stem 7 out of the nut 5, until the threads 6 of the stem are free of the threads 14 of the nut 5, will result in the small terminal convolution 15a at the lower end of the retainer E resting upon shoulder 13 formed by the upper side of the nut 5 in the socket A, thereby preventing complete removal of the floor-engaging section B from the socket section A, which frequently takes place when chairs and other articles equipped with adjustable floor-engaging elements are slid or dragged over the floor in a manner to cause counterclockwise rotation of the stem of the floor-engaging element with respect

to the threaded portion of the socket firmly secured in the article.

In that form of the invention shown in Figs. 1 to 3 inclusive, the neck 16 of the stem 7, from the underside of the head 17 to the beginning of the threads 6, is of sufficient length to permit the threads 6 to be backed completely out of the internal threads 14 of the nut 5; whereas, in the modified structure shown in Figs. 6, 7 and 8, the neck 16a is relatively short, whereby the small terminal convolution 15a at the one end of the retainer E1 will engage the top surface of the socket nut 5a before the threads 6a of the stem 7a are completely disengaged from the threads 14a of the nut 5a.

While the latter structure is practical, it is not as preferable as the structure shown in Figs. 1, 2 and 3, for the reason that there is a tendency, should one attempt to force the stem 7a in a counter-clockwise direction, for the free end of the terminal convolution 15a to jamb in the threads 14a of the nut 5a, it being noted that in this instance the convolutions of the retainer E1 are wound right handed in accordance with the right hand thread 6a of the stem 7a.

It will be also noted that in the structure shown in Figs. 1-4 inclusive the convolutions 15 of the retainer E are wound in a counter-direction to the threads on the stem and in the nut 5, in order to prevent any jamming of the terminal convolutions of the retainer E in the threads 14 of the nut 5.

In that form of the invention shown in Figs. 9, 10, 11 and 12 the spring-type retainer E and E1 is replaced by a sleeve-type retainer E2, which is split longitudinally, as indicated at 20, and is adapted to fit snugly around the neck 16b of the stem 7b, between the innermost of the threads 6b on said stem and a shoulder 18b formed in the larger end of the frusto-conical head 17b of the stem 7b. The sleeve-type retainer E2, in this instance, is installed on the stem 7 in substantially the same manner as the spring type of retainer E is installed, as will be obvious by comparison of Figs. 1 and 9, and Figs. 2 and 10.

As shown in Fig. 3 the stem 7b is not permitted to be backed completely out of the nut 5b of the socket structure A2, as a result of the lower end 21 of the sleeve E2 engaging the upper surface 50 shoulder-forming surface 13b of the nut 5b, while the upper end of the sleeve E2 engages the shoulder 18b on the head 17b of the stem 7b.

In that form of the invention shown in Figs. 13, 14, 15 and 16 the spring and sleeve types of retainers E, E1 and E2 are replaced by a cup-type of retainer, shown in Fig. 15. The cup-retainer E3 comprises a crown 23 which is adapted to fit over the small end 19c of the frusto-conical head 17c of the stem 7c, and is provided with a skirt 24 having one or more longitudinal slits 25, to permit the retainer to expand and contract radially. The open end of the cup retainer E3 is provided with an inturned flange 26 which is adapted to snap under the shoulder 18c formed by the larger end of the frusto-conical head 17c of said stem.

As shown in Figs. 13 and 14 the stem 7c is provided with a short neck 16c which prevents the threads 6c of the stem 7c from being backed completely out of the threads 14c of the nut 5c; while the structure shown in Fig. 16 provides the long neck 16d by which complete removal of the threads 6d of the stem 7d from the threads 14d of the nut 5d is permitted.

I claim:

1. A caster structure comprising a hollow socket having an open end, internal threads in said open end, a floor engaging element including a threaded stem for entering said open end to co-operate with said internal threads, an annular shoulder on said stem, and a radially expandable and contractible retainer loosely confined in said socket internally beyond said internal threads said retainer comprising a coiled spring including 10 a plurality of convolutions of one diameter and a terminal convolution of relatively smaller diameter for gripping said stem under said shoulder to cause said retainer to move with said stem in said socket and to prevent withdrawal of said 15 stem from said socket.

2. A caster structure comprising a hollow cup-like base including flat angularly related side walls, a correspondingly flat sided nut seated in said base, a hollow thimble open at one end and 20 axially aligned with said nut and said base, a flange on said thimble resting on said nut, and ears forming part of said side walls bent inwardly over said flange and securing said base nut and thimble together as a unit.

3. A caster structure comprising a hollow cup-like base including flat angularly related side walls, a correspondingly flat sided nut seated in said base, a hollow thimble open at one end and axially aligned with said nut and said base, a flange on said thimble resting on said nut, ears forming part of said side walls bent inwardly over said flange and securing said base nut and thimble together as a unit, and prongs formed on said side walls intermediate said ears for securing said unit to an article to be supported by said caster structure.

4. A caster structure comprising a hollow cup-like base including flat angularly related side walls, a correspondingly flat sided nut seated in said base, a hollow thimble open at one end and axially aligned with said nut and said base, a flange on said thimble resting on said nut, ears forming part of said side walls bent inwardly over said flange and securing said base nut and thimble together as a unit, prongs formed on said side walls intermediate said ears for securing said unit to an article to be supported by said caster structure, and a floor engaging unit comprising a stem threaded through said nut into said hollow thimble.

5. A caster structure comprising a hollow cup-like base including flat angularly related side walls, a correspondingly flat sided nut seated in said base, a hollow thimble open at one end and axially aligned with said nut and said base, a flange on said thimble resting on said nut, ears forming part of said side walls bent inwardly over said flange and securing said base nut and thimble together as a unit, prongs formed on said side walls intermediate said ears for securing said unit to an article to be supported by said caster structure, a floor engaging unit comprising a stem threaded through said nut into said hollow thimble, and means loosely confined in said thimble beyond said nut and secured to said stem to prevent removal of said stem completely from said nut.

6. A caster assembly comprising a hollow socket having an open end, a floor engaging element including a stem of substantially smaller diameter than said hollow socket and adapted to move axially in said socket, an abutment forming the base of said hollow socket, a locking member adapted to slide axially in said socket, 75

a flange adapted to close the open end of the socket after said locking member is inserted in the socket, said flange having a hole therein adapted to permit passage of the stem but to prevent withdrawal of the locking member whereby the locking member may be secured to the stem by pressing the locking member between the stem and the abutment of the socket after the flange is permanently secured to the socket.

7. A caster assembly in accordance with claim 6 in which there is an annular shoulder on the stem adapted to engage the locking member.

8. A caster assembly in accordance with claim 6 in which the locking member comprises a radially distendable element adapted to enclose the stem and having a distended diameter less than the bore of the socket.

9. The method of assembling a caster having a hollow socket, and a stem adapted to rotate in said socket which comprises; inserting a locking member in the socket, permanently securing a flange member at the open end of said socket to prevent removal of the locking member, inserting the stem of a floor engaging element through a hole in said flange, and compressing the locking member between said stem and the base of the socket to permanently engage the locking member and the stem thereby preventing withdrawal of the locking member.

10. An adjustable support for furniture and the like comprising a floor engaging element, a threaded stem attached to said element, the threads on said stem terminating below the upper extremity of the stem, an annular retaining shoulder on the upper extremity of the stem, said shoulder being in spaced axial relation to the terminus of the threads, an annular groove on the stem between the shoulder and the terminus of the thread, the diameter of said groove being less than the root diameter of the threads on the stem, an internally threaded member non-rotatably mounted on said article of furniture, and a radially expandable and contractible retainer adapted to fit over said shoulder so that when the stem is threaded through the bore and the retainer installed over the shoulder, the axial distance between the terminus of the threads on the stem and the retainer is sufficient to permit free turning of the stem in the threaded bore when the threads are completely disengaged whereby the retainer prevents withdrawal of the stem from the bore.

11. Structure in accordance with claim 10, in which, the retainer comprises a coil spring including a plurality of convolutions of one diameter and a terminal convolution of relatively smaller diameter for gripping the stem under the shoulder.
